(57) **ABSTRACT**

An image forming apparatus includes a main-body housing, a drum unit, and a toner cartridge. The drum unit includes a photosensitive drum, a drum frame, a developing roller, a toner-inlet shutter to open and close a toner-inlet opening, a cleaning member, and a collected-toner outlet shutter to open and close a collected-toner outlet opening. The toner cartridge includes a toner casing having a toner container and a collected-toner container, and a shutter-driving member having a transmission device and an operable device. The transmission device is movable by the operable device between a first position, at which the toner-inlet shutter and the collected-toner outlet shutter are located at positions to close the toner-inlet opening and the collected-toner outlet opening, and a second position, at which the toner-inlet shutter and the collected-toner outlet shutter are located at positions to open the toner-inlet opening and the collected-toner outlet opening.

IMAGE FORMING APPARATUS

REFERENCE TO RELATED APPLICATIONS

This application claims priority from Japanese Patent Application No. 2022-151722 filed on Sep. 22, 2022. The entire content of the priority application is incorporated herein by reference.

BACKGROUND ART

A known image forming apparatus includes a main-body housing, a drum unit, and a toner cartridge. The drum unit is located inside the main-body housing. The drum unit may have a photosensitive drum, a drum frame, a developing roller, a toner-inlet shutter, and a cleaning member. The toner-inlet shutter may open or close a toner-inlet opening.

The toner cartridge is mountable in and demountable from the main-body housing. The toner cartridge may have a toner container and a collected-toner container. The toner container may contain toner to be supplied to the photosensitive drum. The collected-toner container may contain the toner collected from the photosensitive drum.

DESCRIPTION

When the toner cartridge is being mounted in the main-body housing of the image forming apparatus, before the toner cartridge is completely mounted in the main-body housing, the toner-inlet shutter may start opening the toner-inlet opening before the toner cartridge is located at a correct position with respect to the toner-inlet opening. Moreover, when the toner cartridge is being demounted from the main-body housing, the toner cartridge may start moving with respect to the main-body housing before the toner-inlet shutter completely closes the toner-inlet opening.

Therefore, when the toner cartridge is being mounted in or demounted from the main-body housing, it may be difficult to restrict the toner from scattering in an area around the toner-inlet opening.

The present disclosure is advantageous in that an image forming apparatus, in which scattering of toner in an area around a toner-inlet opening and leakage of the toner through a collected-toner-outlet opening may be reduced.

FIG. 1 is an illustrative overall view of an image forming apparatus.

FIG. 2 is an illustrative view of a drum unit and a toner cartridge mounted in a main-body housing in the image forming apparatus.

FIG. 3 is an illustrative view of the image forming apparatus with the toner cartridge demounted from the main-body housing.

FIG. 4 is an illustrative view of the image forming apparatus with the drum unit demounted from the main-body housing.

FIG. 5 is a perspective view of the drum unit.

FIG. 6 is a plan view of the drum unit.

FIG. 7 is a cross-sectional view of the drum unit sectioned at a line A-A indicated in FIG. 6.

FIG. 8 is a cross-sectional view of the drum unit sectioned at a line B-B indicated in FIG. 6.

FIG. 9 is a cross-sectional view of the drum unit sectioned at a line C-C indicated in FIG. 6.

FIG. 10 is a cross-sectional view of the drum unit sectioned at a line D-D indicated in FIG. 6 with a transmission member located at a transmission-member first position.

FIG. 11 is a cross-sectional view of the drum unit sectioned at the line D-D indicated in FIG. 6 with the transmission member located at a transmission-member second position.

FIG. 12 is a cross-sectional view of the drum unit sectioned at a line E-E indicated in FIG. 6.

FIG. 13 is a perspective view of the toner cartridge.

FIG. 14 is a cross-sectional view of the toner cartridge sectioned at a line A-A indicated in FIG. 15.

FIG. 15 is a plan view of the toner cartridge with a transmission device located at a first position.

FIG. 16 is a plan view of the toner cartridge with the transmission device located at a second position.

FIG. 17 is a rearward view of the toner cartridge.

1. OVERALL CONFIGURATION OF IMAGE FORMING APPARATUS

With reference to FIGS. 1-4, an overall configuration of an image forming apparatus 1 will be described below. In the following paragraphs, a term "vertical direction" refers to an upright direction in a state where the image forming apparatus 1 is situated on a horizontal plane.

As shown in FIG. 1, the image forming apparatus 1 may print images in multiple colors. The image forming apparatus 1 includes a main-body housing 2, a cover 3 (see FIG. 2), a sheet container 4, a plurality of drum units 5Y, 5M, 5C, 5K, a plurality of toner cartridges 6Y (see FIG. 2), 6M, 6C, 6K, an exposure device 7, an intermediate transfer unit 8, a transfer roller 9, and a fuser 10. The toner cartridges 6M, 6C, 6K may be referred to herein and below for easier explanation but are not in not shown in the drawings.

1.1 Main-Body Housing 2

As shown in FIG. 1, the main-body housing 2 accommodates the sheet container 4, the drum units 5Y, 5M, 5C, 5K, the toner cartridges 6Y (see FIG. 2), 6M, 6C, 6K, the exposure device 7, the intermediate transfer unit 8, the transfer roller 9, and the fuser 10.

As shown in FIG. 3, the main-body housing 2 has a main-body opening 21. The main-body opening 21 is located in an area in the main-body housing 2 on an end of the main-body housing 2 on one side in a first direction.

1.2 Cover 3

As shown in FIGS. 2 and 3, the cover 3 may move between a closed position (see FIG. 2) and an open position (see FIG. 3). When the cover 3 is located at the closed position, as shown in FIG. 2, the cover 3 may close the main-body opening 21. When the cover 3 is located at the open position, as shown in FIG. 3, the cover 3 may open the main-body opening 21.

1.3 Sheet Container 4

As shown in FIG. 1, the sheet container 4 may contain one or more sheets S. The sheets S contained in the sheet container 4 may be conveyed toward the transfer roller 9.

1.4 Drum Units 5Y, 5M 5C, 5K

The drum units 5Y, 5M 5C, 5K are located inside the main-body housing 2. The drum units 5Y, 5M 5C, 5K align in a second direction, which intersects with the first direction. Preferably, the second direction may intersect orthogonally with the first direction. The drum units 5Y, 5M, 5C, 5K are in a same structure; therefore, in the following paragraphs, while the drum unit 5Y will be described in detail, description of the drum units 5M, 5C, 5K will be omitted.

The drum unit 5Y is a drum cartridge mountable in and demountable from the main-body housing 2. Optionally, the drum unit 5Y may not be demountable from the main-body housing 2 but may be mounted in the main-body housing 2

undemountably. In a state where the drum unit **5Y** is mounted in the main-body housing **2**, the drum unit **5Y** is located between the exposure device **7** and the intermediate transfer unit **8** in the vertical direction. In the state where the drum unit **5Y** is mounted in the main-body housing **2**, the drum unit **5Y** is located above the exposure device **7**.

As shown in FIG. 4, in the state where the cover **3** is located at the open position, with the toner cartridge **6Y** demounted from the main-body housing **2**, the drum unit **5Y** is mountable in and demountable from the main-body housing **2** in the first direction through the main-body opening **21**.

As shown in FIG. 1, the drum unit **5Y** includes a photosensitive drum **51Y**, a charger **52Y**, and a developing unit **53Y**.

1.4.1 Photosensitive Drum **51Y**

The photosensitive drum **51Y** is rotatable on a drum axis **A1**. In the state where the drum unit **5Y** is mounted in the main-body housing **2**, the drum axis **A1** extends in the first direction. The photosensitive drum **51Y** extends in the first direction. The photosensitive drum **51Y** has a cylindrical form.

1.4.2 Charger **52Y**

The charger **52Y** may charge the photosensitive drum **51Y**. The charger **52Y** may be, for example, a charging roller. The charger **52Y** may be, for example, a scorotron-styled charger.

1.4.3 Developing Unit **53Y**

The developing unit **53Y** may supply toner to a circumferential surface of the photosensitive drum **51Y** having been exposed to light from the exposure device **7**. The developing unit **53Y** has a developer casing **531Y** and a developing roller **532Y**. In other words, the drum unit **5Y** has a developer casing **531Y** and a developing roller **532Y**.

The developer casing **531Y** may contain the toner to be supplied to the circumferential surface of the photosensitive drum **51Y**. The developer casing **531Y** supports the developing roller **532Y**.

The developing roller **532Y** may supply the toner in the developer casing **531Y** to the photosensitive drum **51Y**. The developing roller **532Y** is in contact with the photosensitive drum **51Y**. Optionally, the developing roller **532Y** may be separable from the photosensitive drum **51Y**. The developing roller **532Y** extends in the first direction. The developing roller **532Y** is rotatable on a developer axis **A2**. In the state where the drum unit **5Y** is mounted in the main-body housing **2**, the developer axis **A2** extends in the first direction.

1.5 Toner Cartridges **6Y**, **6M**, **6C**, **6K**

As shown in FIG. 2, the toner cartridge **6Y** is mountable in and demountable from main-body housing **2**. In particular, in the state where the cover **3** is located at the open position, with the drum unit **5Y** mounted in the main-body housing **2**, as shown in FIG. 3, the toner cartridge **6Y** is movable in the first direction to be mounted in and demounted from the main-body housing **2** through the main-body opening **21**. The toner cartridge **6Y** is mountable in and demountable from the main-body housing **2** by moving with respect to the drum unit **5Y** in the first direction. The toner cartridge **6Y** may contain the toner. As shown in FIG. 2, in the state where the drum unit **5Y** and the toner cartridge **6Y** are mounted in the main-body housing **2**, the toner cartridge **6Y** is connected with the drum unit **5Y** in the first direction.

Meanwhile, in a state where the drum unit **5M** (see FIG. 1) and the toner cartridge **6M** (not shown) are mounted in the main-body housing **2**, the toner cartridge **6M** is connected

with the drum unit **5M** in the first direction. In a state where the drum unit **5C** (see FIG. 1) and the toner cartridge **6C** (not shown) are mounted in the main-body housing **2**, the toner cartridge **6C** is connected with the drum unit **5C** in the first direction. In a state where the drum unit **5K** (see FIG. 1) and the toner cartridge **6K** (not shown) are mounted in the main-body housing **2**, the toner cartridge **6K** is connected with the drum unit **5K** in the first direction. Each of the toner cartridges **6M**, **6C**, **6K** is in the same structure as the toner cartridge **6Y**.

1.6 Exposure Device **7**

As shown in FIG. 1, in the state where the drum units **5Y**, **5M**, **5C**, **5K** are mounted in the main-body housing **2**, the exposure device **7** is located on a lower side of the drum units **5Y**, **5M**, **5C**, **5K**. In the state where the drum units **5Y**, **5M**, **5C**, **5K** are mounted in the main-body housing **2**, the exposure device **7** may emit exposure light at the circumferential surface of the photosensitive drum **51Y** charged by the charger **52Y**, a circumferential surface of the photosensitive drum **51M** charged by the charger **52M**, a circumferential surface of the photosensitive drum **51C** charged by the charger **52C**, and a circumferential surface of the photosensitive drum **51K** charged by the charger **52K**. The exposure device **7** may be, for example, a laser scanner unit. For another example, the exposure device **7** may be LED heads.

1.7 Intermediate Transfer Unit **8**

In the state where the drum units **5Y**, **5M**, **5C**, **5K** are mounted in the main-body housing **2**, the intermediate transfer unit **8** is located on an upper side of the drum units **5Y**, **5M**, **5C**, **5K**. The intermediate transfer unit **8** has an intermediate transfer belt **81** and transfer rollers **82Y**, **82M**, **82C**, **82K**.

In the state where the drum units **5Y**, **5M**, **5C**, **5K** are mounted in the main-body housing **2**, the intermediate transfer belt **81** is in contact with the photosensitive drums **51Y**, **51M**, **51C**, **51K**.

The transfer roller **82Y** may serve to transfer the toner on the photosensitive drum **51Y** to the intermediate transfer belt **81**. The transfer roller **82M** may serve to transfer the toner on the photosensitive drum **51M** to the intermediate transfer belt **81**. The transfer roller **82C** may serve to transfer the toner on the photosensitive drum **51C** to the intermediate transfer belt **81**. The transfer roller **82K** may serve to transfer the toner on the photosensitive drum **51K** to the intermediate transfer belt **81**.

1.8 Transfer Roller **9**

The transfer roller **9** may serve to transfer the toners on the intermediate transfer belt **81** to the sheet **S**. In particular, the sheet **S** fed from the sheet container **4** to the transfer roller **9** may be conveyed, through a position between the transfer roller **9** and the intermediate transfer belt **81**, to the fuser **10**. In the meantime, the transfer roller **9** may serve to transfer the toners on the intermediate transfer belt **81** to the sheet **S**.

1.9 Fuser **10**

The fuser **10** may apply heat and pressure to the sheet **S** to fix the toners transferred thereon. The sheet **S** exiting the fuser **10** may be ejected on an upper face of the main-body housing **2**.

2. DETAILS OF DRUM UNIT **5Y**

Detailed configuration of the drum unit **5Y** will be described below with reference to FIGS. 5-12.

As shown in FIG. 5, the drum unit **5Y** includes a drum frame **54Y**, a toner tube **55Y**, a first conveying member **56Y** (see FIG. 10), a toner-inlet shutter **57Y**, a drum cleaner **58Y**,

an outlet **59Y** (see FIG. 10), a collected-toner outlet shutter **60Y**, a transmission member **61Y**, a locking member **62Y**, and a sealing member **63Y** (see FIG. 9).

2.1 Drum Frame **54Y**

The drum frame **54Y** supports the photosensitive drum **51Y** rotatably. As shown in FIG. 6, the drum frame **4Y** has a first side plate **541A**, a second side plate **541B**, and a third side plate **541C**.

2.1.1 First Side Plate **541A**

The first side plate **541A** is located at one end of the drum frame **54Y** on the one side in the first direction. The first side plate **541A** extends in a direction intersecting with the first direction. Preferably, the first side plate **541A** extends in a direction intersecting orthogonally with the first direction. The first side plate **541A** supports one end of the photosensitive drum **51Y** on the one side in the first direction. As shown in FIG. 7, the first side plate **541A** has two (2) through-holes **5411A**, **5412A**.

The through-hole **5411A** is located apart from the photosensitive drum **51Y** in a third direction. The third direction is a direction of a line connecting the drum axis **A1** and the developer axis **A2**. The through-hole **5411A** extends in the third direction. The through-hole **5411A** is an ellipse-formed hole.

The through-hole **5412A** is located between the through-hole **5411A** and the photosensitive drum **51Y** in the third direction. The through-hole **5412A** is located apart from the through-hole **5411A** in the third direction. The through-hole **5412A** extends in the third direction. The through-hole **5412A** is an ellipse-formed hole.

2.1.2 Second Side Plate **541B**

As shown in FIG. 6, the second side plate **541B** is located on the other end of the drum frame **54Y** on the other side in the first direction. The second side plate **541B** is located apart from the first side plate **541A** in the first direction. The second side plate **541B** extends in a direction intersecting with the first direction. Preferably, the second side plate **541B** extends in the direction intersecting orthogonally with the first direction. The second side plate **541B** supports the other end of the photosensitive drum **51Y** on the other side in the first direction. The second side plate **541B** has two (2) through-holes **5411B**, **5412B**.

The through-hole **5411B** is located at the same position in the third direction (see FIG. 7) as the through-hole **5411A** in the first side plate **541A** apart from the photosensitive drum **51Y**. The through-hole **5411B** extends in the third direction. The through-hole **5411B** is an ellipse-formed hole.

The through-hole **5412B** is located at the same position in the third direction as the through-hole **5412A** in the first side plate **541A** apart from the photosensitive drum **51Y**. The through-hole **5412B** is located apart from the through-hole **5411B** in the third direction. The through-hole **5412B** extends in the third direction. The through-hole **5412B** is an ellipse-formed hole.

2.1.3 Third Side Plate **541C**

The third side plate **541C** is located on the one side of the drum frame **54Y** in the first direction. The third side plate **541C** extends in a direction intersecting with the first direction. Preferably, the third side plate **541C** extends in the direction intersecting orthogonally with the first direction. The third side plate **541C** is located farther than the first side plate **541A** from the second side plate **541B** in the first direction. The third side plate **541C** is located on a side of the first side plate **541A** opposite to the second side plate **541B** in the first direction.

2.2 Details of Developing Unit **53Y**

As shown in FIG. 5, the developing unit **53Y** is located between the first side plate **541A** and the second side plate **541B** in the first direction. As shown in FIG. 6, the developing unit **53Y** has, further to the developer casing **531Y** and the developing roller **532Y** (see FIG. 8), two (2) protrusions **533A**, **534A** and two (2) protrusions **533B**, **534B**.

2.2.1 Details of Developer Casing **531Y**

The developer casing **531Y** is located between the first side plate **541A** and the second side plate **541B** in the first direction. The developer casing **531Y** extends in the first direction. As shown in FIG. 8, the developer casing **531** has a divider wall **5310** and an inlet **5311** (see FIG. 9).

The divider wall **5310** divides a space inside the developer casing **531Y** into a first developing compartment **530A** and a second developing compartment **530B**. In other words, the developer casing **531Y** has a first developing compartment **530A** and a second developing compartment **530B**. The first developing compartment **530A** accommodates a part of the developing roller **532A**. The second developing compartment **530B** may contain toner to be supplied to the first developing compartment **530A**. The divider wall **5310** has a flow-in port **5310A**. The toner in the second developing compartment **530B** may enter the first developing compartment **530A** through the flow-in port **5310A**.

As shown in FIG. 6, the inlet **5311** is located at one end of the developer casing **531Y** on the one side in the first direction. The inlet **5311** extends in the first direction. The inlet **5311** has a cylindrical form. A space inside the inlet **5311** is continuous with the second developing compartment **530B** (see FIG. 8). As shown in FIG. 9, the inlet **5311** has an inlet opening **5311A**. Through the inlet opening **5311A**, toner from the toner tube **55Y** may be received in the developer casing **531Y**.

2.2.2 Protrusions **533A**, **534A**

As shown in FIG. 6, the protrusion **533A** is located on one end of the developing unit **53Y** on the one side in the first direction. The protrusion **533A** extends in the first direction. According to the present embodiment, the protrusion **533A** extends outward from an outer surface of the developer casing **531** on the one side in the first direction. Optionally, the protrusion **533A** may be attached to the outer surface of the developer casing **531** on the one side in the first direction. As shown in FIG. 7, the protrusion **533A** is located apart from the photosensitive drum **51Y** in the third direction. The protrusion **533A** has a cylindrical form. The protrusion **533A** is located in the through-hole **5411A** in the first side plate **541A**.

As shown in FIG. 6, the protrusion **534A** is located on the one end of the developing unit **53Y** on the one side in the first direction. The protrusion **534A** extends in the first direction. For example, the protrusion **534A** may be a part of a shaft of the developing roller **532Y** on one end on the one side in the first direction. Optionally, for another example, the protrusion **534A** may extend outward from the outer surface of the developer casing **531** on the one side in the first direction. Optionally, the protrusion **534A** may be attached to the outer surface of the developer casing **531** on the one side in the first direction. As shown in FIG. 7, the protrusion **534A** is located between the photosensitive drum **51Y** and the protrusion **533A**. The protrusion **534A** has a cylindrical form. The protrusion **534A** is located in the through-hole **5412A** in the first side plate **541A**.

2.2.3 Protrusions **533B**, **534B**

As shown in FIG. 6, the protrusion **533B** is located on the other end of the developing unit **53Y** on the other side in the first direction. The protrusion **533B** is located in the through-hole **5411B** in the second side plate **541B**. The protrusion

533B is in the same form as the protrusion 533A; therefore, detailed description of the protrusion 533B is herein omitted.

The protrusion 534B is located on the other end of the developing unit 53Y on the other side in the first direction. The protrusion 534B is located in the through-hole 5412B in the second side plate 541B. The protrusion 534B is in the same form as the protrusion 534A; therefore, detailed description of the protrusion 534B is herein omitted.

With the protrusion 533A located in the through-hole 5411A, the protrusion 534A located in the through-hole 5412A, the protrusion 533B located in the through-hole 5411B, and the protrusion 534B located in the through-hole 5412B, the developing unit 53Y is supported by the drum frame 54Y. The developing unit 53Y is movable with respect to the photosensitive drum 51Y in the third direction. In other words, the developer casing 531Y is movable with respect to the photosensitive drum 51Y.

2.3 Toner Tube 55Y

As shown in FIG. 5, the toner tube 55Y is located on one end of the drum unit 5Y on the one side in the first direction. The toner tube 55Y extends in the first direction. The toner tube 55Y has a toner-tube body 551Y and a shutter-supporting portion 552Y.

2.3.1 Toner-Tube Body 551Y

The toner-tube body 551Y extends in the first direction. The toner-tube body 551Y has a cylindrical form. The toner-tube body 551Y extends through the first side plate 541A. The toner-tube body 551Y is supported by the first side plate 541A. One end of the toner-tube body 551Y in the first direction is located on a side of the first side plate 541A opposite to the developer casing 531. The other end of the toner-tube body 551Y in the first direction is located between the developer casing 531Y and the first side plate 541A. The toner-tube body 551Y has a toner-inlet opening 5511 (see FIG. 6) and a toner-supplying opening 5512 (see FIG. 9). In other words, the toner tube 55Y has a toner-inlet opening 5511 and a toner-supplying opening 5512. The toner tube 55Y allows the toner to travel therein from the toner-inlet opening 5511 to the toner-supplying opening 5512.

As shown in FIG. 6, the toner-inlet opening 5511 is located in an area on one end of the toner tube 55Y in the first direction. The toner-inlet opening 5511 is located on a side of the first side plate 541A opposite to the developer casing 531Y in the first direction. As shown in FIG. 10, the toner-inlet opening 5511 is continuous with a space inside the toner-tube body 551Y. In the state where the drum unit 5Y and the toner cartridge 6Y are mounted in the main-body housing 2, the toner from the toner cartridge 6Y (see FIG. 2) may be received in the toner tube 55Y through the toner-inlet opening 5511.

As shown in FIG. 9, the toner-supplying opening 5512 is located in an area on the other end of the toner tube 55Y in the first direction. The toner-supplying opening 5512 is located between the first side plate 541A (see FIG. 6) and the developer casing 531Y (see FIG. 6) in the first direction. The toner-supplying opening 5512 is located on the same side of the first side plate 541A of the drum frame 54Y as the developer casing 531Y. The toner-supplying opening 5512 is continuous with the inlet opening 5311A of the developer casing 531Y. The space inside the toner-tube body 551Y is continuous with a space inside the inlet 5311 of the developer casing 531Y through the toner-supplying opening 5512 and the inlet opening 5311A. Therefore, the toner may be supplied from the toner tube 55Y through the toner-supplying opening 5512 to the developer casing 531Y.

2.3.2 Sutter Supporting Portion 552Y

As shown in FIG. 5, the shutter-supporting portion 552Y aligns with the toner-tube body 551Y in a radial direction of the toner-tube body 551Y. The shutter-supporting portion 552Y extends in the first direction. The shutter-supporting portion 552Y has a cylindrical form. The shutter-supporting portion 552Y is connected to a circumferential surface of the toner-tube body 551Y. The shutter-supporting portion 552Y supports the toner-inlet shutter 57Y. The shutter-supporting portion 552Y supports one end of the third side plate 541C on the one side of the first side plate 541A.

2.4 First Conveying Member 56Y

As shown in FIG. 10, the first conveying member 56Y is located inside the toner tube 55Y. In particular, the first conveying member 56Y is located inside the toner-tube body 551Y. The first conveying member 56Y may convey the toner in the toner-tube body 551Y toward the toner-supplying opening 5512 (see FIG. 9). The first conveying member 56Y extends in the first direction. The first conveying member 56Y may be, for example, an auger screw.

2.5 Toner-Inlet Shutter 57Y

As shown in FIG. 5, the toner-inlet shutter 57Y is located on the one end of the drum unit 5Y on the one side in the first direction. The toner-inlet shutter 57Y is located inside the shutter-supporting portion 552Y. The toner-inlet shutter 57Y may open or close the toner-inlet opening 5511. The toner-inlet shutter 57Y extends in the first direction. The toner-inlet shutter 57Y has a cylindrical form. The toner-inlet shutter 57Y is rotatable between a position, at which the toner-inlet shutter 57Y closes the toner-inlet opening 5511 (see FIG. 10), and a position, at which the toner-inlet shutter 57Y opens the toner-inlet opening 5511 (see FIG. 11). The toner-inlet shutter 57Y has an opening 571Y, a gear portion 572Y (see FIG. 12), and two (2) holes 573Y, 574Y (see FIG. 12).

2.5.1 Opening 571Y

The opening 571Y is formed through a circumference surface of the toner-inlet shutter 57Y. As shown in FIG. 10, in a state where the toner-inlet shutter 57Y closes the toner-inlet opening 5511, the opening 571Y is not connected with the toner-inlet opening 5511. As shown in FIG. 11, in a state where the toner-inlet shutter 57Y opens the toner-inlet opening 5511, the opening 571Y is continuous with the toner-inlet opening 5511.

2.5.2 Gear Portion 572Y

As shown in FIG. 6, the gear portion 572Y is located on an end of the toner-inlet shutter 57Y toward the other side in the first direction. The gear portion 572Y is located outside the shutter-supporting portion 552Y. The gear portion 572Y is located between the toner-inlet shutter 57Y and the third side plate 541C in the first direction. Moreover, the gear portion 572Y is located between the shutter-supporting portion 552Y and the third side plate 541C in the first direction. The gear portion 572Y is located apart from the opening 571Y in the first direction. As shown in FIG. 12, the gear portion 572Y is located on a circumferential surface of the toner-inlet shutter 57Y. The gear portion 572Y has gear teeth. The gear teeth protrude from the circumferential surface of the toner-inlet shutter 57Y. The gear teeth align along a rotating direction of the toner-inlet shutter 57Y. Optionally, the gear teeth may be attached to the circumferential surface of the toner-inlet shutter 57Y.

2.5.3 Holes 573Y, 574Y

The hole 573Y is located on the end of the toner-inlet shutter 57Y toward the other side in the first direction. The hole 573Y is formed through an inner face of the toner-inlet shutter 57Y.

The hole **574Y** is located on the end of the toner-inlet shutter **57Y** toward the other side in the first direction. The hole **573Y** is formed through the inner face of the toner-inlet shutter **57Y**. The hole **574Y** is located apart from the hole **573Y** a radial direction of the toner-inlet shutter **57Y**

2.6 Drum Cleaner **58Y**

As shown in FIG. 6, the drum cleaner **58Y** is located between the first side plate **541A** and the second side plate **541B** in the first direction. The drum cleaner **58Y** may clean the circumferential surface of the photosensitive drum **51Y**. As shown in FIG. 8, the drum cleaner **58Y** includes a cleaning member **581Y**, a cleaner casing **582Y**, and a second conveying member **583Y**. In other words, the drum unit **5Y** has a cleaning member **581Y**

2.6.1 Cleaning Member **581Y**

The cleaning member **581Y** may clean the circumferential surface of the photosensitive drum **51Y**. The cleaning member **581Y** may collect the toner remaining on the circumferential surface of the photosensitive drum **51Y** without being transferred from the photosensitive drum **51Y** to the intermediate transfer belt **81** (see FIG. 1). The toner collected by the cleaning member **581Y** from the circumferential surface of the photosensitive drum **51Y** will be hereafter called collected toner. The cleaning member **581Y** is attached to the cleaner casing **582Y**. For example, the cleaning member **581Y** may be in a form of a blade. An edge of the cleaning member **581Y** contacts the circumferential surface of the photosensitive drum **51Y**. The cleaning member **581Y** may be, or another example, a roller.

2.6.2 Cleaner Casing **582Y**

As shown in FIG. 6, the cleaner casing **582Y** is located between the first side plate **541A** and the second side plate **541B** in the first direction. The cleaner casing **582Y** extends in the first direction. One end of the cleaner casing **582Y** on the one side in the first direction is connected to the first side plate **541A**. The other end of the cleaner casing **582Y** on the other side in the first direction is connected to the second side plate **541B**. The cleaner casing **582Y** may store the collected toners.

2.7 Second Conveying Member **583Y**

The second conveying member **583Y** is located inside the cleaner casing **582Y**. The second conveying member **583Y** extends in the first direction. The second conveying member **583Y** may convey the collected toner toward the outlet **59Y**. The second conveying member **583Y** extends through the first side plate **541A** and the third side plate **541C**. The second conveying member **583Y** may be, for example, an auger screw.

2.8 Outlet **59Y**

The outlet **59Y** is located on the one end of the drum unit **5Y** on the one side in the first direction. The outlet **59Y** is located on a side of the first side plate **541A** opposite to the cleaner casing **582Y**. The outlet **59Y** extends in the first direction. The outlet **59Y** has a cylindrical form. A space inside the outlet **59Y** is continuous with a space inside the cleaner casing **582Y**. On end of the second conveying member **583Y** on the one side in the first direction is located inside the outlet **59Y**. As shown in FIG. 10, the outlet **59Y** has a collected-toner-outlet opening **591Y**. The outlet **59Y** supports the other end of the third side plate **541C** toward the other side in the first direction. The outlet **59Y** extends through the third side plate **541C**.

2.8.1 Collected-Toner Outlet Opening **591Y**

The collected-toner-outlet opening **591Y** is located on a side of the first side plate **541A** of the drum frame **54Y** opposite to the developer casing **531Y** in the first direction. The collected-toner-outlet opening **591Y** is formed through

a circumferential surface of the outlet **59Y**. The collected-toner-outlet opening **591Y** is continuous with the space inside the outlet **59Y**. Through the collected-toner-outlet opening **591Y**, the collected toner may be discharged outside the outlet **59Y**.

2.9 Collected-Toner Outlet Shutter **60Y**

As shown in FIG. 6, the collected-toner outlet shutter **60Y** is located on the one end of the drum unit **5Y** on the one side in the first direction. The collected-toner outlet shutter **60Y** is located on a side of the first side plate **541A** and the third side plate **541C** opposite to the cleaner casing **582Y** in the first direction. The collected-toner outlet shutter **60Y** may open and close the collected-toner-outlet opening **591Y**. As shown in FIG. 10, the collected-toner outlet shutter **60Y** is located on the circumferential surface of the outlet **59Y**. The collected-toner outlet shutter **60Y** has a cylindrical form. The collected-toner outlet shutter **60Y** extends in the first direction. As shown in FIGS. 10 and 11, the collected-toner outlet shutter **60Y** is rotatable between a position, at which the collected-toner outlet shutter **60Y** closes the collected-toner-outlet opening **591Y** (see FIG. 10), and a position, at which the collected-toner outlet shutter **60Y** opens the collected-toner-outlet opening **591Y** (see FIG. 11). As shown in FIG. 11, the collected-toner outlet shutter **60Y** has an opening **601Y**, a gear portion **602Y**, and two (2) engaging portions **603A, 603B** (see FIG. 5).

2.9.1 Opening **601Y**

The opening **601Y** is formed through a circumferential surface of the collected-toner outlet shutter **60Y**. As shown in FIG. 10, in the state where the collected-toner outlet shutter **60Y** closes the collected-toner-outlet opening **591Y**, the opening **601Y** is not continuous with the collected-toner-outlet opening **591Y**. As shown in FIG. 11, in the state where the collected-toner outlet shutter **60Y** opens the collected-toner-outlet opening **591Y**, the opening **601Y** is continuous with the collected-toner-outlet opening **591Y**.

2.9.2 Gear Portion **602Y**

As shown in FIG. 6, the gear portion **602Y** is located on an end of the collected-toner outlet shutter **60Y** toward the other side in the first direction. The gear portion **602Y** is located apart from the opening **601Y** in the first direction. The gear portion **602Y** is located on the side of the first side plate **541A** and the third side plate **541C** opposite to the cleaner casing **582Y** in the first direction. As shown in FIG. 12, the gear portion **602Y** is located on the circumferential surface of the collected-toner outlet shutter **60Y**. The gear portion **602Y** has gear teeth protruding from the circumferential surface of the collected-toner outlet shutter **60Y**. The gear teeth align along a rotating direction of the collected-toner outlet shutter **60Y**. The gear teeth are attached to the circumferential surface of the collected-toner outlet shutter **60Y**.

2.9.3 Engaging Portions **603A, 603B**

As shown in FIG. 5, the engaging portion **603A** is located on one end of the collected-toner outlet shutter **60Y** on the one side in the first direction. The engaging portion **603A** is located on an outer surface of the collected-toner outlet shutter **60Y**. The engaging portion **603A** in the present embodiment is a protrusion. The engaging portion **603A** protrudes in the first direction.

The engaging portion **603B** is located on the one end of the collected-toner outlet shutter **60Y** on the one side in the first direction. The engaging portion **603B** is located on the outer surface of the collected-toner outlet shutter **60Y**. The engaging portion **603B** is located apart from the engaging portion **603A** in a radial direction of the collected-toner outlet shutter **60Y**. The engaging portion **603B** in the present

embodiment is a protrusion. The engaging portion 603B protrudes in the first direction.

2.10 Transmission Member 61Y

As shown in FIG. 12, the transmission member 61Y is located between the toner-inlet shutter 57Y and the collected-toner outlet shutter 60Y in the second direction. The transmission member 61Y is located on a side of the third side plate 541C opposite to the first side plate 541A in the first direction. The transmission member 61Y may be, for example, a gear. The transmission member 61Y meshes with the gear portion 572Y and the gear portion 602Y. In other words, the transmission member 61Y is coupled to both the toner-inlet shutter 57Y and the collected-toner outlet shutter 60Y. The gear portion 572Y meshes with the transmission member 61Y. The gear portion 602Y meshes with the transmission member 61Y.

The transmission member 61Y is rotatably supported by a rotation shaft of the third side plate 541C. The rotation shaft of the third side plate 541C is not shown in the drawings.

Optionally, the transmission member 61Y may be a pulley. In the case where the transmission member 61Y is a pulley, in place of the gear portion 672, a belt may be strained around the transmission member 61Y and the circumferential surface of the toner-inlet shutter 57Y; and in place of the gear portion 602Y, a belt may be strained around the transmission member 61Y and the circumferential surface of the collected-toner outlet shutter 60Y.

Optionally, for another example, the transmission member 61Y may be a link. In the case where the transmission member 61Y is a link, in place of the gear portion 572, the drum unit 5Y may be provided with a first coupler that couples a part of the circumferential surface of the toner-inlet shutter 57Y with a part of the transmission member 61Y; and in place of the gear portion 602Y, the drum unit 5Y may be provided with a second coupler that couples a part of the collected-toner outlet shutter 60Y with a part of the transmission member 61Y.

As shown in FIGS. 10 and 11, by rotating the transmission member 61Y, the toner-inlet shutter 57Y may move between a position, at which the toner-inlet shutter 57Y closes the toner-inlet opening 5511 (see FIG. 10), and a position, at which the toner-inlet shutter 57Y opens the toner-inlet opening 5511 (see FIG. 11). By rotating the transmission member 61Y, further, the collected-toner outlet shutter 60Y may move between a position, at which the collected-toner outlet shutter 60Y closes the collected-toner-outlet opening 591Y (see FIG. 10), and a position, at which the collected-toner outlet shutter 60Y opens the collected-toner outlet opening 591Y (see FIG. 11).

The transmission member 61Y is rotatable between a transmission-member first position (see FIG. 10) and a transmission-member second position (see FIG. 11).

As shown in FIG. 10, in the state where the transmission member 61Y is located at the transmission-member first position, the toner-inlet shutter 57Y is located at the position to close the toner-inlet opening 5511, and the collected-toner outlet shutter 60Y is located at the position to close the collected-toner-outlet opening 591Y.

As shown in FIG. 11, in the state where the transmission member 61Y is located at the transmission-member second position, the toner-inlet shutter 57Y is located at the position to open the toner-inlet opening 5511, and the collected-toner outlet shutter 60Y is located at the position to open the collected-toner-outlet opening 591Y.

The transmission member 61Y has a recess 611Y.

2.10.1 Recess 611Y

As shown in FIG. 12, the recess 611Y is formed to dent in a direction intersecting orthogonally with the first direction. In the state where the toner cartridge 6Y and the drum unit 5Y are mounted in the main-body housing 2, the recess 611Y fits with a transmission device 761Y of the toner cartridge 6Y. The transmission device 761Y will be described further below. The form of the recess 611Y may not necessarily be limited as long as the transmission member 61Y is rotatable along with the transmission device 761Y in a state where the transmission device 761Y of the toner cartridge 6Y fits in the recess 611Y. In the present embodiment, the recess 611Y has a first part 6111 and two (2) second parts 6112, 6113.

2.10.2 First Part 6111

The first part 6111 is located at a center in a radial direction of the transmission member 61Y. The first part 6111 may have, for example, a circular form.

2.10.3 Second Parts 6112, 6113

The second part 6112 is located on one side of the first part 6111 in the radial direction of the transmission member 61Y. The second part 6112 is continuous with the first part 6111. The second part 6112 extends in the radial direction of the transmission member 61Y. The second part 6112 has a rectangular form.

The second part 6113 is located on the other side of the first part 6111 opposite to the second part 6112 in the radial direction of the transmission member 61Y. The second part 6113 is continuous with the first part 6111. The second part 6113 extends in the radial direction of the transmission member 61Y. The second part 6113 has a rectangular form.

2.11 Locking Member 62Y

As shown in FIG. 6, the locking member 62Y is located on a side of the transmission member 61Y opposite to the first side plate 541A in the first direction. The locking member 62Y extends in a direction intersecting with the first direction. In particular, the locking member 62Y may extend in the second direction. The locking member 62Y may have, for example, a form of a plate.

2.11.1 Through-Hole 621Y

As shown in FIG. 10, the locking member 62Y has a through-hole 621Y. The through-hole 621Y is located between the toner-inlet shutter 57Y and the collected-toner outlet shutter 60Y in the second direction.

The through-hole 621Y extends in a direction intersecting orthogonally with a pass-through direction. The pass-through direction is a direction, in which the transmission device 761Y passes through the through-hole 621Y. For example, the pass-through direction may be the first direction. In particular, the through-hole has a first part 6211 and two (2) second parts 6212, 6213.

2.11.2 First Part 6211

The first part 6211 is located at a longitudinal center in a direction, in which the through-hole 621Y extends. The first part 6211 may have, for example, a circular form. The first part 6222 overlaps the first part 6111 of the transmission member 61Y in the first direction.

2.11.3 Second Parts 6212, 6213

The second part 6212 is located on one side of the first part 6211 in a radial direction of first part 6211. The second part 6212 is continuous with the first part 6111. The second part 6212 extends in the radial direction of the first part 6211. The second part 6212 has a rectangular form.

The second part 6213 is located on the other side of the first part 6211 opposite to the second part 6212 in the radial direction of first part 6211. The second part 6213 is continuous with the first part 6111. The second part 6213

extends in the radial direction of the first part **6211**. The second part **6213** has a rectangular form.

As shown in FIG. 10, in the state where the transmission member **61Y** is located at the transmission-member first position, the second part **6112** of the transmission member **61Y** overlaps the second part **6212** of the locking member **62Y** in the first direction, and the second part **6113** of the transmission member **61Y** overlaps the second part **6213** of the locking member **62Y** in the first direction.

As shown in FIG. 11, in the state where the transmission member **61Y** is located at the transmission-member second position, the second part **6112** of the transmission member **61Y** is displaced from the second parts **6212**, **6213** of the locking member **62Y** in the rotating direction of the transmission member **61Y**, and the second part **6113** of the transmission member **61Y** is displaced from the second parts **6212**, **6213** of the locking member **62Y** in the rotating direction of the transmission member **61Y**. Therefore, in the state where the transmission member **61Y** is located at the transmission-member second position, the second part **6112** of the transmission member **61Y** does not overlap the second part **6212** or the second part **6213** of the locking member **62Y** in the first direction, and the second part **6113** of the transmission member **61Y** does not overlap the second part **6212** or the second part **6213** of the locking member **62Y** in the first direction.

2.12 Sealing Member **63Y**

As shown in FIG. 9, the sealing member **63Y** is located between the inlet **5311** and the other end of the toner tube **55Y** in the first direction. The sealing member **63Y** is located around the inlet opening **5311A** of the inlet **5311** and around the toner-supplying opening **5512** of the toner tube **55Y**. The sealing member **63Y** seals a gap between the inlet **5311** and the other end of the toner tube **55Y** in the first direction. The sealing member **63Y** is elastically deformable according to the developing unit **53Y** moving with respect to the photosensitive drum **51Y**. The sealing member **63Y** may consist of, for example, sponge.

3. DETAILS OF TONER CARTRIDGE **6Y**

With reference to FIGS. 2 and 13-17, a detailed configuration of the toner cartridge **6Y** will be described below. In the following context, a vertical direction, a first direction, and a second direction refer to directions concerning the toner cartridge **6Y** in the state where the toner cartridge **6Y** and the drum unit **5Y** are mounted in the main-body housing **2**.

As shown in FIG. 13, the toner cartridge **6Y** has a toner casing **71Y**, a toner outlet **72Y**, a toner-outlet shutter **73Y**, a collected-toner inlet **74Y**, a collected-toner inlet shutter **75Y**, and a shutter-driving member **76Y**.

3.1 Toner Casing **71Y**

The toner casing **71Y** extends in the vertical direction and the first direction. The toner casing **71Y** has a first face **71A** and a second face **71B** on one side and the other side in the first direction. As shown in FIG. 2, in the state where the toner cartridge **6Y** and the drum unit **5Y** are mounted in the main-body housing **2**, the second face **71B** is located between the first face **71A** and the drum unit **5Y** in the first direction. In the state where the toner casing **71Y** is mounted in the main-body housing **2**, the first face **71A** is located on a side of the second face **71B** opposite to the drum unit **5Y**. As shown in FIG. 14, the toner casing **71Y** has a toner container **711Y** and a collected-toner container **712Y**.

3.1.1 Toner Container **711Y**

The toner container **711Y** is located above the collected-toner container **712Y**. The toner container **711Y** may contain the toner to be supplied to the photosensitive drum **51Y** (see FIG. 5).

3.1.2 Collected-Toner Container **712Y** The collected-toner container **712Y** is located below and apart from the toner container **711Y**. The collected-toner container **712Y** may contain the collected toner.

3.2 Toner Outlet **72Y**

As shown in FIG. 13, the toner outlet **72Y** is located at a lower end of the toner container **711Y**. Through the toner outlet **72Y**, the toner in the toner container **711Y** may be discharged. As shown in FIG. 15, the toner outlet **72Y** has a toner-outlet tube **721Y** and a third conveying member **722Y**.

3.2.1 Toner-Outlet Tube **721Y**

The toner-outlet tube **721Y** is located on the second face **71B**, i.e., on a side of the toner casing **71Y** opposite to the first face **71A** in the first direction. The toner-outlet tube **721Y** extends in the first direction. The toner-outlet tube **721Y** extends from the second face **71B**. Optionally, the toner-outlet tube **721Y** may be attached to the second face **71B**. A space inside the toner-outlet tube **721Y** is continuous with a space inside the toner container **711Y**. The toner-outlet tube **721Y** may have a cylindrical form. The toner-outlet tube **721Y** has a toner-outlet opening **7211**.

3.2.2 Toner-Outlet Opening **7211**

The toner-outlet opening **7211** is formed through a circumferential surface of the toner-outlet tube **721Y**. The toner-outlet opening **7211** is continuous with the space inside the toner-outlet tube **721Y**. In the state where the toner cartridge **6Y** and the drum unit **5Y** are mounted in the main-body housing **2**, and in the state where the toner-inlet shutter **57Y** (see FIG. 11) and the toner-outlet shutter **73Y** are open, the toner-outlet opening **7211** is continuous with the toner-inlet opening **5511** (see FIG. 11). In the state where the toner cartridge **6Y** is mounted in the main-body housing **2**, and in the state as shown in FIG. 16, the toner in the toner container **711Y** (see FIG. 14) may be discharged through the toner-outlet opening **7211** into the toner-inlet opening **5511** of the drum unit **5Y**.

3.2.3 Third Conveying Member **722Y**

The third conveying member **722Y** is located inside the toner-outlet tube **721Y** and the toner container **711Y**. The third conveying member **722Y** extends in the third direction. The third conveying member **722Y** may convey the toner in the toner container **711Y** toward the toner-outlet opening **7211**. The third conveying member **722Y** may be, for example, an auger screw.

3.3 Toner-Outlet Shutter **73Y**

As shown in FIG. 15, the toner-outlet shutter **73Y** is located on an end of the toner cartridge **6Y** toward the other side in the first direction. The toner-outlet shutter **73Y** is located on a side of the second face **71B** opposite to the first face **71A** in the first direction. The toner-outlet shutter **73Y** extends in the first direction. The toner-outlet shutter **73Y** has a cylindrical form. The toner-outlet shutter **73Y** is located on the circumferential surface of the toner-outlet tube **721Y**. The toner-outlet shutter **73Y** may open and close the toner-outlet opening **7211**. As shown in FIGS. 15 and 16, the toner-outlet shutter **73Y** is rotatable between a position (see FIG. 15), at which the toner-outlet shutter **73Y** closes the toner-outlet opening **7211**, and a position (see FIG. 16), at which the toner-outlet shutter **73Y** opens the toner-outlet opening **7211**.

15

The toner-outlet shutter 73Y has an opening 731Y (see FIG. 15) and two (2) engaging portions 732Y, 733Y (see FIG. 13).

3.3.1 Opening 731Y

As shown in FIG. 15, the opening 731Y is formed through a circumferential surface of the toner-outlet shutter 73Y. The opening 731Y is, in the state where the toner-outlet shutter 73Y closes the toner-outlet opening 7211, not continuous with the toner-outlet opening 7211. As shown in FIG. 16, in the state where the toner-outlet shutter 73Y opens the toner-outlet opening 7211, the opening 731Y is continuous with the toner-outlet opening 7211.

3.3.2 Engaging Portions 732Y, 733Y

As shown in FIG. 13, the engaging portion 732Y is located on an end of the toner-outlet shutter 73Y toward the other side in the first direction. The engaging portion 732Y is located on an outer face of the toner-outlet shutter 73Y in the first direction. The engaging portion 732Y may be, for example, a protrusion. The engaging portion 732Y extends in the first direction.

The engaging portion 733Y is located on the end of the toner-outlet shutter 73Y toward the other side in the first direction. The engaging portion 733Y is located on the outer face of the toner-outlet shutter 73Y in the first direction. The engaging portion 733Y is located apart from the engaging portion 732Y in a radial direction of the toner-outlet shutter 73Y. The engaging portion 733Y may be, for example, a protrusion. The engaging portion 733Y extends in the first direction.

As shown in FIG. 2, in the state where the toner cartridge 6Y and the drum unit 5Y are mounted in the main-body housing 2, the toner-outlet shutter 73Y and the toner outlet 72Y are inserted in the toner-inlet shutter 57Y (see FIG. 10) of the drum unit 5Y. While the toner-outlet shutter 73Y and the toner outlet 72Y are inserted in the toner-inlet shutter 57Y, the toner-outlet opening 7211 is located above the toner-inlet opening 5511 (see FIG. 10) of the drum unit 5Y.

While the toner-outlet shutter 73Y and the toner outlet 72Y are inserted in the toner-inlet shutter 57Y, the engaging portion 732Y fits in the hole 573Y (see FIG. 10) in the drum unit 5Y, and the engaging portion 733Y fits in the hole 574Y (see FIG. 10) in the drum unit 5Y. Thus, the toner-outlet shutter 73Y of the toner cartridge 6Y engages with the toner-inlet shutter 57Y in the drum unit 5Y.

Accordingly, the toner-outlet shutter 73Y is, in the state where the toner cartridge 6Y and the drum unit 5Y are mounted in the main-body housing 2, movable along with the toner-inlet shutter 57Y (see FIG. 10) of the drum unit 5Y.

In particular, as shown in FIG. 15, in the state where the toner-inlet shutter 57Y (see FIG. 10) is located at the position to close the toner-inlet opening 5511 (see FIG. 10), the toner-outlet shutter 73Y is located at the position to close the toner-outlet opening 7211.

On the other hand, as shown in FIG. 16, in the state where the toner-inlet shutter 57Y (see FIG. 11) is located at the position to open the toner-inlet opening 5511 (see FIG. 11), the toner-outlet shutter 73Y is located at the position to open the toner-outlet opening 7211.

3.4 Collected-Toner Inlet 74Y

As shown in FIG. 13, the collected-toner inlet 74Y is located at an upper end of the collected-toner container 712. The collected-toner inlet 74Y is located apart from the toner outlet 72Y in the second direction. As shown in FIG. 15, the collected-toner inlet 74Y has a collected-toner inlet tube 741Y and a fourth conveying member 742Y.

16

3.4.1 Collected-Toner Inlet Tube 741Y

The collected-toner inlet tube 741Y is located on the second face 71B, i.e., on the side of the toner casing 71Y opposite to the first face 71A in the first direction. A space 5 inside the collected-toner inlet tube 741Y is continuous with a space inside the collected-toner container 712. The collected-toner inlet tube 741Y may have a cylindrical form. As shown in FIG. 13, the collected-toner inlet tube 741Y has a collected-toner inlet tube body 7411 and a shutter-supporting portion 7412.

3.4.2 Collected-Toner Inlet Tube Body 7411

The collected-toner inlet tube body 7411 is located on the second face 71B, i.e., on the side of the toner casing 71Y opposite to the first face 71A in the first direction. The 15 collected-toner inlet tube body 7411 extends from the second face 71B. Optionally, the collected-toner inlet tube body 7411 may be attached to the second face 71B. The collected-toner inlet tube body 7411 extends in the first direction. The collected-toner inlet tube body 7411 may have a cylindrical form. A space inside the collected-toner inlet tube body 7411 is continuous with a space inside the collected-toner container 712Y. The collected-toner inlet tube body 7411 has a collected-toner-inlet opening 7410.

The collected-toner-inlet opening 7410 is formed through 25 a circumferential surface of the collected-toner inlet tube body 7411. The collected-toner-inlet opening 7410 is continuous with the space inside the collected-toner inlet tube body 7411. In the state where the toner cartridge 6Y and the drum unit 5Y are mounted in the main-body housing 2, and 30 in a state where the collected-toner-outlet opening 591Y of the drum unit 5Y and the collected-toner-inlet opening 7410 are open, the collected toner from the outlet 59Y (see FIG. 11) of the drum unit 5Y may be received in the collected-toner inlet tube body 7411 through the collected-toner opening 7410.

3.4.3 Shutter-Supporting Portion 7412

The shutter-supporting portion 7412 aligns with the collected-toner inlet tube body 7411 in a radial direction of the collected-toner inlet tube body 7411. The shutter-supporting portion 7412 extends in the first direction. The shutter-supporting portion 7412 has a cylindrical form. The shutter-supporting portion 7412 is connected to the circumferential surface of the collected-toner inlet tube body 7411. The shutter-supporting portion 7412 supports the collected-toner inlet shutter 75Y.

3.4.4 Fourth Conveying Member 742Y

As shown in FIG. 15, the fourth conveying member 742Y is located inside the collected-toner inlet tube 741Y and the collected-toner container 712Y. The fourth conveying member 742Y extends in the first direction. The fourth conveying member 742Y may convey the collected toner from the collected-toner inlet opening 7410 (see FIG. 15) to the collected-toner container 712Y. The fourth conveying member 742Y may be, for example, an auger screw.

3.5 Collected-Toner Inlet Shutter 75Y

As shown in FIG. 13, the collected-toner inlet shutter 75Y is located on the end of the toner cartridge 6Y toward the other side in the first direction. The collected-toner inlet shutter 75Y is located inside the shutter-supporting portion 7412. The collected-toner inlet shutter 75Y has a cylindrical form. The collected-toner inlet shutter 75Y extends in the first direction. The collected-toner inlet shutter 75Y may open and close the collected-toner inlet opening 7410. As shown in FIGS. 15 and 16, the collected-toner inlet shutter 75Y is rotatable between a position (see FIG. 15), at which the collected-toner inlet shutter 75Y closes the collected-toner inlet opening 7410, and a position (see FIG. 16), at

which the collected-toner inlet shutter 75Y opens the collected-toner inlet opening 7410. The collected-toner inlet shutter 75Y has an opening 751Y and two (2) holes 752Y, 753Y (see FIG. 16).

3.5.1 Opening 751Y

As shown in FIG. 15, the opening 751Y is formed through a circumferential surface of the collected-toner inlet shutter 75Y. The opening 751Y is, in the state where the collected-toner inlet shutter 75Y closes the collected-toner inlet opening 7410, not continuous with the collected-toner inlet opening 7410. As shown in FIG. 16, in the state where the collected-toner inlet shutter 75Y opens the collected-toner inlet opening 7410, the opening 751Y is continuous with the collected-toner inlet opening 7410.

3.5.2 Holes 752Y, 753Y

As shown in FIG. 16, the hole 752Y is located on an end of the collected-toner inlet shutter 75Y toward the one side in the first direction. The hole 752Y is located on an inner surface of the collected-toner inlet shutter 75Y.

The hole 753Y is located on the end of the collected-toner inlet shutter 75Y toward the one side in the first direction. The hole 753Y is located on the inner surface of the collected-toner inlet shutter 75Y. The hole 753Y is located apart from the hole 752Y in a radial direction of the collected-toner inlet shutter 75Y.

As shown in FIG. 2, in the state where the toner cartridge 6Y and the drum unit 5Y are mounted in the main-body housing 2, the collected-toner outlet shutter 60Y and the outlet 59Y (see FIG. 10) are inserted in the collected-toner inlet shutter 75Y (see FIG. 13). In this arrangement, the collected-toner inlet opening 7410 of the collected-toner inlet 74Y is located below the collected-toner outlet opening 591Y.

In the state where the collected-toner outlet shutter 60Y and the outlet 59Y are inserted in the collected-toner inlet shutter 75Y, the engaging portion 603A (see FIG. 5) of the drum unit 5Y fits in the hole 752Y, and the engaging portion 603B (see FIG. 5) of the drum unit 5Y fits in the hole 753Y. Accordingly, the collected-toner inlet shutter 75Y of the toner cartridge 6Y engages with the collected-toner outlet shutter 60Y of the drum unit 5Y.

Therefore, in the state where the toner cartridge 6Y and the drum unit 5Y are mounted in the main-body housing 2, the collected-toner inlet shutter 75Y is enabled to move along with the collected-toner outlet shutter 60Y of the drum unit 5Y.

As shown in FIG. 15, in particular, in the state where the collected-toner outlet shutter 60Y (see FIG. 10) is located at the position to close the collected-toner outlet opening 591Y (see FIG. 10), the collected-toner inlet shutter 75Y is located at the position to close the collected-toner inlet opening 7410.

As shown in FIG. 16, in the state where the collected-toner outlet shutter 60Y (see FIG. 11) is located at the position to open the collected-toner outlet opening 591Y (see FIG. 11), the collected-toner inlet shutter 75Y is located at the position to open the collected-toner inlet opening 7410.

In the state where the toner cartridge 6Y and the drum unit 5Y are mounted in the main-body housing 2, when the collected-toner inlet opening 7410 opens, the collected toner, discharged from the outlet 59Y through the collected-toner outlet opening 591Y (see FIG. 14), may be received in the collected-toner inlet tube body 7411 through the collected-toner inlet opening 7410.

3.6 Shutter-Driving Member 76Y

As shown in FIG. 14, the shutter-driving member 76Y is located between the toner container 711Y and the collected-toner container 712Y in the vertical direction. As shown in FIG. 15, the shutter-driving member 76Y is located between the toner-outlet shutter 73Y and the collected-toner inlet shutter 75Y in the second direction. The shutter-driving member 76Y has a transmission device 761Y, an operable device 762Y, and a shaft 763Y.

3.6.1 Transmission Device 761Y

The transmission device 761Y is located at a tip of the shutter-driving member 76Y. The transmission device 761Y is located on the side of the second face 71B opposite to the first face 71A in the first direction. The transmission device 761Y is located apart from the second face 71B in the first direction.

The transmission device 761Y is rotatable on an axis A3. The axis A3 extends in the first direction. The transmission device 761Y has a shaft 7611 and two (2) protrusions 7612, 7613.

3.6.1.1 Shaft 7611

The shaft 7611 extends in the first direction. The shaft 7611 has a cylindrical form.

3.6.1.2 Protrusions 7612, 7613

As shown in FIG. 16, the protrusion 7612 extends in a radial direction of the shaft 7611. The protrusion 7612 extends from a circumferential surface of the shaft 7611. Optionally, the protrusion 7612 may be attached to the circumferential surface of the shaft 7611.

The protrusion 7613 extends in the radial direction of the shaft 7611. The protrusion 7613 extends from the circumferential surface of the shaft 7611. Optionally, the protrusion 7613 may be attached to the circumferential surface of the shaft 7611. The protrusion 7613 is located on a side of the shaft 7611 opposite to the protrusion 7612.

The transmission device 761Y is movable between a first position and a second position.

As shown in FIG. 15, in a state where the transmission device 761Y is located at the first position, the protrusions 7612, 7613 both protrude from the shaft 7611 in the vertical direction. According to the present embodiment, the through-hole 621Y in the locking member 62Y extends in the vertical direction. The protrusions 7612, 7613 may protrude in a direction along the vertical direction.

Therefore, as shown in FIG. 2, in the state where the toner cartridge 6Y and the drum unit 5Y are mounted in the main-body housing 2, the transmission device 761Y passes through the through-hole 621Y of the locking member 62Y of the drum unit 5Y (see FIG. 10) and fits in the recess 611Y of the transmission member 61Y located at the transmission-member first position. In particular, the shaft 7611 fits in the first part 611 (see FIG. 12) of the transmission member 61Y, the protrusion 7612 fits in the second part 6112 of the transmission member 61Y, and the protrusion 7613 fits in the second part 6113 of the transmission member 61Y. Thus, the transmission member 61Y engages with the transmission member 61Y. In other words, in the state where the toner cartridge 6Y is mounted in the main-body housing 2, the transmission member 61Y is engaged with the transmission device 761Y.

Therefore, in the state where the toner cartridge 6Y is mounted in the main-body housing 2, the transmission device 761Y may transmit power input thereto to the toner-inlet shutter 57Y (see FIG. 5) and the collected-toner outlet shutter 60Y (see FIG. 5).

As shown in FIG. 15, in the state where the transmission device 761Y is located at the first position, the transmission

device 761Y locates the transmission member 61Y at the transmission-member first position. As described earlier, when the transmission member 61Y is located at the transmission-member first position, as shown in FIG. 10, the toner-inlet shutter 57Y is located at the position to close the toner-inlet opening 5511, and the collected-toner outlet shutter 60Y is located at the position to close the collected-toner outlet opening 591Y. In other words, in the state where the transmission device 761Y is located at the first position, the transmission device 761Y locates the toner-inlet shutter 57Y at the position to close the toner-inlet opening 5511 and locates the collected-toner outlet shutter 60Y at the position to close the collected-toner outlet opening 591Y.

On the other hand, as shown in FIG. 16, in the state where the transmission device 761Y is located at the second position, the transmission device 761Y locates the transmission member 61Y at the transmission-member second position. As described earlier, when the transmission member 61Y is located at the transmission-member second position, as shown in FIG. 11, the toner-inlet shutter 57Y is located at the position to open the toner-inlet opening 5511, and the collected-toner outlet shutter 60Y is located at the position to open the collected-toner outlet opening 591Y. In other words, in the state where the transmission device 761Y is located at the second position, the transmission device 761Y locates the toner-inlet shutter 57Y at the position to open the toner-inlet opening 5511 and locates the collected-toner outlet shutter 60Y at the position to open the collected-toner outlet opening 591Y.

Thus, in the state where the toner cartridge 6Y and the drum unit 5Y are mounted in the main-body housing 2, the shutter-driving member 76Y may drive the toner-inlet shutter 57Y (see FIG. 5) and the collected-toner outlet shutter 60Y (see FIG. 5).

Meanwhile, as shown in FIG. 16, in the state where the transmission device 761Y is located at the second position, the protrusions 7612, 1673 protrude in the second direction.

Therefore, in the state where the toner cartridge 6Y and the drum unit 5Y are mounted in the main-body housing 2, with the transmission device 761Y being located at the second position, the protrusion 7612 of the transmission device 761Y does not overlap the second part 6212 (see FIG. 11) of the through-hole 621Y in the locking member 62Y in the first direction, and the protrusion 7613 of the transmission device 761Y does not overlap the second part 6213 (see FIG. 11) of the through-hole 621Y in the locking member 62Y in the first direction.

Accordingly, in the state where the toner cartridge 6Y and the drum unit 5Y are mounted in the main-body housing 2, with the transmission device 761Y being located at the second position, when the toner cartridge 6Y moves in a demounting direction, in which the toner cartridge 6Y is demounted from the main-body housing 2, e.g., the first direction, the locking member 62Y may collide with the transmission device 761Y and stop the toner cartridge 6Y from moving further in the demounting direction.

It may be noted that the form of the transmission device 761Y may not necessarily be limited as long as the cross-sectional shape thereof has convexity or concavity. For example, a number of the protrusions may not necessarily be limited to two. For another example, the transmission device 761Y may have a polygonal cross-sectional form, and the shaft 7611 and the protrusions 7612, 7613 may be formed integrally. For another example, the transmission device 761Y may have a rectangular cross-sectional form.

3.6.2 Operable Device 762Y

As shown in FIG. 15, the operable device 762Y is located on an end of the shutter-driving member 76Y in the first direction. The operable device 762Y is located on a side of the toner casing 71Y opposite to the transmission device 761Y. The operable device 762Y may move the transmission device 761Y between the first position (see FIG. 15) and the second position (see FIG. 16). For example, the operable device 762Y may be a handle. Preferably, the operable device 762Y may be foldable, as shown in FIG. 17. In the state where the toner cartridge 6Y is mounted in the main-body housing 2, as shown in FIG. 2, the operable device 762Y is located inside the cover 3. Optionally, the operable device 762Y may be a knob in, for example, a cylindrical form.

3.6.3 Shaft 763Y

As shown in FIG. 15, the shaft 763Y extends in the first direction. The shaft 763Y penetrates the toner casing 71Y. In the present embodiment, the shaft 763Y has a cylindrical form. Meanwhile, the form of the shaft 763Y is not necessarily limited but may have, for example, a columnar form with a rectangular or C- or U-shaped cross section. The shaft 763Y is rotatable with respect to the toner casing 71Y. The shaft 763Y connects the transmission device 761 and the operable device 762Y. Optionally, a part of the shaft 763Y may form the operable device 762Y.

4. DETAILS OF IMAGE FORMING APPARATUS

30 With reference to FIGS. 2 and 3, the image forming apparatus 1 will be described in detail.

As shown in FIG. 2, the image forming apparatus 1 has a supporting member 11 and a receiver member 12.

35 4.1 Supporting Member 11

According to the present embodiment, the supporting member 11 is located in a lower area in the image forming apparatus 1. The supporting member 11 is located in the image forming apparatus 1 on the one side in the first direction. The supporting member 11 extends in the first direction. The supporting member 11 may be, for example, in a form of a board. The supporting member 11 may support the toner cartridge 6Y.

45 As shown in FIGS. 2 and 3, in the state where the supporting member 11 supports the toner cartridge 6Y, the supporting member 11 may move in the first direction between an inner position (see FIG. 2) and an outer position (see FIG. 3).

50 As shown in FIG. 2, in the state where the supporting member 11 is located at the inner position, the supporting member 11 locates the toner cartridge 6Y at the position inside the main-body housing 2.

55 As shown in FIG. 3, in the state where the supporting member 11 is located at the outer position, the supporting member 11 locates the toner cartridge 6Y at a position outside the main-body housing 2.

4.2 Receiver Member 12

As shown in FIG. 3, the receiver member 12 is located below the outlet 59Y (see FIG. 11) of the drum unit 5Y 60 located inside the main-body housing 2. In other words, the receiver member 12 is located below the collected-toner outlet opening 591Y (see FIG. 11) of the drum unit 5Y located inside the main-body housing 2. The receiver member 12 may receive the collected toner falling through a gap 65 between the collected-toner outlet opening 591Y and the collected-toner inlet opening 7410 (see FIG. 15). The receiver member 12 has a form of sheet. The receiver

member 12 extends in the first direction. The receiver member 12 may consist of, for example, sponge.

As shown in FIG. 2, in the state where the supporting member 11 is located at the inner position, the supporting member 11 is located between the collected-toner outlet opening 591Y (see FIG. 11) and the receiver member 12 in the vertical direction.

As shown in FIG. 3, in the state where the supporting member 11 is located at the outer position, the supporting member 11 is not located between the collected-toner outlet opening 591Y (see FIG. 11) and the receiver member 12 in the vertical direction.

5. MOUNTING AND DEMOUNTING TONER CARTRIDGE 6Y IN AND FROM MAIN-BODY HOUSING 2 WITH DRUM UNIT 5Y

5.1 Mounting Toner Cartridge 6Y in Main-Body Housing 2 with Drum Unit 5Y

With reference to FIGS. 2-3 and 15, a mounting procedure of the toner cartridge 6Y in the main-body housing 2 with the drum unit 5Y will be described.

5.2 Mounting Toner Cartridge 6Y in Main-Body Housing 2

A procedure of mounting the toner cartridge 6Y in the main-body housing 2 will be described herein.

As shown in FIG. 3, in the state where the drum unit 5 is mounted in the main-body housing 2, a user may open the cover 3 and locate the supporting member 11 at the outer position.

Next, the user may place the toner cartridge 6Y on an upper face of the supporting member 11. Meanwhile, as shown in FIG. 15, the toner-outlet shutter 73Y of the toner cartridge 6Y is located at the position to close the toner-outlet opening 721, and the collected-toner inlet shutter 75Y is located at the position to close the collected-toner inlet opening 7410.

Next, as shown in FIG. 2, the user may move the supporting member 11 from the outer position to the inner position, insert the toner-outlet shutter 73Y and the toner outlet 72Y (see FIG. 15) into the toner-inlet shutter 57Y (see FIG. 5) of the drum unit 5Y, and insert the collected-toner outlet shutter 60Y (see FIG. 5) and the outlet 59Y into the collected-toner inlet shutter 75Y (see FIG. 15).

In the state where the supporting member 11 is located at the inner position, the toner-outlet opening 7211 is located above the toner-inlet opening 5511 (see FIG. 10) of the drum unit 5Y, and the collected-toner inlet opening 7410 of the collected-toner inlet 74Y is located below the collected-toner outlet opening 591Y. Further, the toner-outlet shutter 73Y (see FIG. 13) of the toner cartridge 6Y engages with the toner-inlet shutter 57Y (see FIG. 5) of the drum unit 5Y, and the collected-toner-inlet shutter 75 (see FIG. 13) of the toner cartridge 6Y engages with the collected-toner outlet shutter 60Y (see FIG. 5) of the drum unit 5Y.

Moreover, the transmission device 761Y (see FIG. 13) of the toner cartridge 6Y passing through the through-hole 621Y (see FIG. 10) of the locking member 62Y of the drum unit 5Y fits in the recess 611Y (see FIG. 12) of the transmission member 61Y.

Thereby, the toner cartridge 6Y is located at a correct position with respect to the drum unit 5Y.

Next, with the toner cartridge 6Y located at the correct position with respect to the drum unit 5Y, the user may rotate the operable device 762Y. Accordingly, the transmission device 761Y may rotate from the first position to the second position, and the transmission member 61Y of the drum unit

5Y may move from the transmission-member first position to the transmission-member second position.

Accordingly, the toner-inlet opening 5511 (see FIG. 11) of the drum unit 5Y opens, the toner-outlet opening 7211 (see FIG. 16) of the toner cartridge 6Y opens, the collected-toner outlet opening 591Y (see FIG. 11) of the drum unit 5Y opens, and the collected-toner inlet opening 7410 (see FIG. 16) of the toner cartridge 6Y opens.

5.3 Demounting Toner Cartridge 6Y from Main-Body Housing 2

For demounting the toner cartridge 6Y from the main-body housing 2, the user may open the cover 3 and rotate the operable device 762Y. Accordingly, the transmission device 761Y moves from the second position to the first position, and the transmission member 61Y of the drum unit 5Y moves from the transmission-member second position to the transmission-member first position.

In this arrangement, the toner-inlet shutter 57Y of the drum unit 5Y closes the toner-inlet opening 5511 (see FIG. 10), the toner-outlet shutter 73Y closes the toner-outlet opening 7211 (see FIG. 15), the collected-toner outlet shutter 60Y of the drum unit 5Y closes the collected-toner outlet opening 591Y (see FIG. 10), and the collected-toner inlet shutter 75Y of the toner cartridge 6Y closes the collected-toner inlet opening 7410 (see FIG. 15).

Further, as shown in FIG. 3, the user may move the supporting member 11 from the inner position to the outer position and draw the toner cartridge 6Y outward from the main-body housing 2. Accordingly, the toner-outlet shutter 73Y and toner shutter 72Y (see FIG. 13) are disengaged from the toner-inlet shutter 57Y (see FIG. 5) of the drum unit 5Y, and the collected-toner outlet shutter 60Y and the outlet 59Y are disengaged from the collected-toner inlet shutter 75Y.

6. BENEFITS

(1) According to the image forming apparatus 1, as shown in FIG. 2, in the state where the toner cartridge 6Y is mounted in the main-body housing 2, the transmission device 761Y of the shutter-driving member 76Y in the toner cartridge 6Y is enabled to transmit the power input thereto to the toner-inlet shutter 57Y and the collected-toner outlet shutter 60Y.

Therefore, in the state where the toner cartridge 6Y is mounted in the main-body housing 2, the user may open and close the toner-inlet shutter 57Y and the collected-toner outlet shutter 60Y by operating the shutter-driving member 76Y.

Accordingly, in the state where the toner cartridge 6Y is located at the correct position with respect to the toner-inlet shutter 57Y and the collected-toner outlet shutter 60Y, the toner-inlet shutter 57Y and the collected-toner outlet shutter 60Y may be opened or closed.

Therefore, scattering of the toner in the area around the toner-inlet opening 5511 and leakage of the toner from the collected-toner outlet opening 591Y may be prevented or reduced.

Moreover, in the state where the toner cartridge 6Y is mounted in the main-body housing 2, the user may move the transmission device 761Y from the side of the toner casing 71Y opposite to the transmission device 761Y by operating the operable device 762Y.

Moreover, in the state where the toner cartridge 6Y is mounted in the main-body housing 2, both the toner-inlet shutter 57Y and the collected-toner outlet shutter 60Y may be opened by the single action to move the transmission

device 761Y from the first position (see FIG. 15) to the second position (see FIG. 16). Furthermore, in the state where the toner cartridge 6Y is mounted in the main-body housing 2, both the toner-inlet shutter 57Y and the collected-toner outlet shutter 60Y may be closed by the single action to move the transmission device 761Y from the second position (see FIG. 16) to the first position (see FIG. 15).

Therefore, the user may open and close the toner-inlet shutter 57Y and the collected-toner outlet shutter 60Y by the simple actions.

(2) According to the image forming apparatus 1, in the state where the toner cartridge 6Y is mounted in the main-body housing 2, the transmission member 61Y of the drum unit 5Y is enabled to move along with the transmission device 761Y of the toner cartridge 6Y.

Therefore, in the state where the toner cartridge 6Y is mounted in the main-body housing 2, by moving the transmission device 761Y of the toner cartridge 6Y, the transmission member 61 of the drum unit 5Y may open and close the toner-inlet shutter 57Y and the collected-toner outlet shutter 60Y.

(3) As shown in FIG. 10, the transmission member 61Y is a gear; therefore, with the transmission member 61Y meshing with the gear portion 572Y, the toner-inlet shutter 57Y may open and close the toner-inlet opening 5511 efficiently. Moreover, with the transmission member 61Y meshing with the gear portion 602Y, the collected-toner outlet shutter 60Y may open and close the collected-toner outlet opening 591Y efficiently.

(4) As shown in FIG. 6, according to the image forming apparatus 1, the developer casing 531Y is supported by the drum frame 54Y at the position between the first side plate 541A and the second side plate 541B movably with respect to the photosensitive drum 51Y. The drum unit 5Y has the toner-supplying opening 5512 (see FIG. 9), through which the toner may be supplied from the toner cartridge 6Y to the developer casing 531Y. The toner-supplying opening 5512 is formed in the toner tube 55Y, and the toner-inlet opening 5511 and the collected-toner outlet opening 591Y are located on the side of the first side plate 541A of the drum frame 54Y opposite to the developer casing 531Y.

Therefore, in the state where the drum unit 5Y is mounted in the main-body housing 2, when the toner cartridge 6Y is being mounted in the main-body housing 2, the toner cartridge 6Y may be located at the correct position with respect to the toner-inlet opening 5511 and the collected-toner outlet opening 591Y on the side of the first side plate 541A opposite to the developer casing 531Y, regardless of the position of the developer casing 531Y.

Accordingly, in the state where the drum unit 5Y is mounted in the main-body housing 2, the toner cartridge 6Y may be mounted in the main-body housing 2 easily.

(5) According to the image forming apparatus 1, in the state where the transmission device 761Y is located at the second position, if, for example, the user erroneously moves the toner cartridge 6Y in the demounting direction, the locking member 62Y may collide with the transmission device 761Y to restrict further movement of the toner cartridge 6Y in the demounting direction. Therefore, scattering of the toner in the area around the toner-inlet opening 5511 and leakage of the toner from the collected-toner outlet opening 591Y may be prevented or reduced.

(6) According to the image forming apparatus 1, the toner-outlet shutter 73Y is enabled to move along with the toner-inlet shutter 57Y of the drum unit 5Y in the state where the toner cartridge 6Y is mounted in the main-body housing 2. The toner-inlet shutter 57Y is enabled to move along with

the collected-toner outlet shutter 60Y of the drum unit 5Y in the state where the toner cartridge 6Y is mounted in the main-body housing 2.

Therefore, in the state where the toner cartridge 6Y is mounted in the main-body housing 2, according to the movement of the shutter-driving member 76Y, the toner-outlet shutter 73Y may open and close in conjunction with the opening/closing movement of the toner-inlet shutter 57Y. Thus, in the state where the toner-outlet opening 7211 is located at the correct position with respect to the toner-inlet opening 5511, the toner-outlet opening 7211 may be opened and closed.

Further, in the state where the toner cartridge 6Y is mounted in the main-body housing 2, according to the movement of the shutter-driving member 76Y, the collected-toner inlet shutter 75Y may open and close in conjunction with the opening/closing movement of the collected-toner outlet shutter 60Y. Thus, in the state where the collected-toner inlet opening 7410 is located at the correct position with respect to the collected-toner outlet opening 591Y, the collected-toner inlet opening 7410 may be opened and closed.

In the state where the toner cartridge 6Y is mounted in the main-body housing 2, with the toner-inlet shutter 57Y located at the position to open the toner-inlet opening 5511, the toner-outlet shutter 73Y is located at the position to open the toner-outlet opening 7211. Therefore, leakage of the toner through the toner-outlet opening 7211 may be prevented or reduced.

In the state where the toner cartridge 6Y is mounted in the main-body housing 2, with the collected-toner outlet shutter 60Y located at the position to open the collected-toner outlet opening 591Y, the collected-toner inlet shutter 75Y is located at the position to open the collected-toner inlet opening 7410. Therefore, scattering of the toner in the area around the collected-toner inlet opening 7410 may be prevented or reduced.

(7) According to the image forming apparatus 1, in the state where the supporting member 11 is located at the inner position, the supporting member 11 allows the toner cartridge 6Y to be located and mounted correctly in the main-body housing 2 easily.

Further, in the state where the supporting member 11 is located at the outer position, the receiver member 12 may receive the collected toner that failed to enter the collected-toner inlet 74Y through the collected-toner inlet opening 7410.

While the invention has been described in conjunction with example structures outlined above and illustrated in the figures, various alternatives, modifications, variations, improvements, and/or substantial equivalents, whether known or that may be presently unforeseen, may become apparent to those having at least ordinary skill in the art. Accordingly, the example embodiments of the disclosure, as set forth above, are intended to be illustrative of the invention, and not limiting the invention. Various changes may be made without departing from the spirit and scope of the disclosure. Therefore, the disclosure is intended to embrace all known or later developed alternatives, modifications, variations, improvements, and/or substantial equivalents.

For example, the image forming apparatus 1 may not necessarily have a plurality of drum units 5Y, 5M, 5C, 5K and a plurality of toner cartridges 6Y, 6M, 6C, 6K but may have a single drum unit, e.g., the drum unit 5K, and a single toner cartridge, e.g., the toner cartridge 6K, alone.

What is claimed is:

1. An image forming apparatus, comprising:
  - a main-body housing;
  - a drum unit located inside the main-body housing; and
  - a toner cartridge mountable in and demountable from the main-body housing,
 wherein the drum unit includes:
  - a photosensitive drum;
  - a drum frame supporting the photosensitive drum rotatably;
  - a developing roller configured to supply toner to the photosensitive drum;
  - a toner-inlet shutter configured to open and close a toner-inlet opening through which the toner to be supplied to the photosensitive drum is receivable from the toner cartridge;
  - a cleaning member configured to clean a circumferential surface of the photosensitive drum; and
  - a collected-toner outlet shutter configured to open and close a collected-toner outlet opening through which collected toner being the toner collected from the circumferential surface of the photosensitive drum by the cleaning member is dischargeable,
 wherein the toner cartridge includes:
  - a toner casing including:
    - a toner container configured to contain the toner to be supplied to the photosensitive drum; and
    - a collected-toner container configured to contain the collected toner; and
  - a shutter-driving member configured to, in a state where the toner cartridge is mounted in the main-body housing, drive the toner-inlet shutter and the collected-toner outlet shutter, the shutter-driving member including:
    - a transmission device configured to, in the state where the toner cartridge is mounted in the main-body housing, transmit power input thereto to the toner-inlet shutter and the collected-toner outlet shutter, the transmission device being movable between a first position, at which the transmission device locates the toner-inlet shutter at a position to close the toner-inlet opening and the collected-toner outlet shutter at a position to close the collected-toner outlet opening, and a second position, at which the transmission device locates the toner-inlet shutter at a position to open the toner-inlet opening and the collected-toner outlet shutter at a position to open the collected-toner outlet opening; and
    - an operable device located on a side of the toner casing opposite to the transmission device, the operable device being configured to move the transmission device between the first position and the second position.
2. The image forming apparatus according to claim 1, wherein the drum unit further includes a transmission member connected with the toner-inlet shutter and with the collected-toner outlet shutter, the transmission member being, in the state where the toner cartridge is mounted in the main-body housing, movable along with the transmission device of the toner cartridge.
3. The image forming apparatus according to claim 2, wherein
  - the transmission member is a gear,
  - the toner-inlet shutter has a first gear portion, the first gear portion meshing with the transmission member, and

the collected-toner outlet shutter has a second gear portion, the second gear portion meshing with the transmission member.

4. The image forming apparatus according to claim 3, wherein, in the state where the toner cartridge is mounted in the main-body housing, the gear is engaged with the transmission device.

5. The image forming apparatus according to claim 1, wherein

the photosensitive drum is rotatable on an axis extending in a first direction, the drum frame includes:

- a first side plate supporting a first end of the photosensitive drum in the first direction; and
- a second side plate supporting a second end of the photosensitive drum opposite to the first end in the first direction,

the drum unit includes:

a developer casing located between the first side plate and the second side plate in the first direction, the developer casing being configured to contain the toner to be supplied to the photosensitive drum, the developer casing supporting the developing roller, the developer casing being movable with respect to the photosensitive drum; and

a toner tube having a toner-supplying opening, the toner-supplying opening being configured to supply the toner to the developer casing there-through, the toner tube allowing the toner to travel there-through from the toner-inlet opening to the toner-supplying opening,

the toner supplying opening is located on a same side of the first side plate of the drum frame as the developer casing, and

the toner-inlet opening and the collected-toner outlet opening are located on a side of the first side plate of the drum frame opposite to the developer casing.

6. The image forming apparatus according to claim 1, wherein the shutter-driving member is a shaft connecting the transmission device and the operable device, the shaft penetrating the toner casing.

7. The image forming apparatus according to claim 1, wherein the drum unit further includes a locking member, the locking member being configured to, in the state where the toner cartridge is mounted in the main-body housing, with the transmission device being located at the second position, and in a case where the toner cartridge is moved in a demounting direction, in which the toner cartridge is demountable from the main-body housing, collide with the transmission device to restrict further movement of the toner cartridge in the demounting direction.

8. The image forming apparatus according to claim 7, wherein the locking member has a through-hole through which the transmission device located at the first position is configured to pass and the transmission device located at the second position is configured not to pass.

9. The image forming apparatus according to claim 8, wherein

the through-hole extends in a particular direction intersecting with a pass-through direction in which the transmission device passes through the through-hole, and

the transmission device has a protrusion protruding in a direction intersecting with the pass-through direction and with the particular direction, in a state where the drum unit and the toner cartridge are mounted in the

27

main-body housing with the locking member being located at the second position.

10. The image forming apparatus according to claim 1, wherein

the toner cartridge further includes:

a toner-outlet shutter configured to, in the state where the toner cartridge is mounted in the main-body housing, open and close a toner-outlet opening through which the toner in the toner container is dischargeable toward the toner-inlet opening of the drum unit, the toner-outlet shutter being movable along with the toner-inlet shutter of the drum unit in the state where the toner cartridge is mounted in the main-body housing; and

a collected-toner inlet shutter configured to, in the state where the toner cartridge is mounted in the main-body housing, open and close a collected-toner inlet opening through which the toner discharged from the collected-toner outlet opening is receivable, the collected-toner inlet shutter being movable along with the collected-toner outlet shutter of the drum unit in the state where the toner cartridge is mounted in the main-body housing,

the toner-outlet shutter engages with the toner-inlet shutter, the toner-outlet shutter being configured to be located at a position to close the toner-outlet opening in a state where the toner-inlet shutter is located at the position to close the toner-inlet opening, the toner-outlet shutter being configured to be located at a position to open the toner-outlet opening in a state where the toner-inlet shutter is located at the position to open the toner-inlet opening, and

the collected-toner inlet shutter engages with the collected-toner outlet shutter, the collected-toner inlet shutter being configured to be located at a position to close the collected-toner inlet opening in a state where the collected-toner outlet shutter is located at the position to close the collected-toner outlet opening, the collected-toner inlet shutter being configured to be located at a position to open the collected-toner inlet

28

opening in a state where the collected-toner outlet shutter is located at the position to open the collected-toner outlet opening.

11. The image forming apparatus according to claim 10,

5 wherein

the photosensitive drum is rotatable on an axis extending in a first direction, and
the toner cartridge is movable in the first direction with respect to the drum unit to be mounted in and demountable from the main-body housing.

10 12. The image forming apparatus according to claim 11, further comprising a supporting member configured to support the toner cartridge, the supporting member being movable in the first direction between an inner position at which the supporting member supports and locates the toner cartridge inside the main-body housing, and an outer position at which the supporting member supports and locates the toner cartridge outside the main-body housing.

15 13. The image forming apparatus according to claim 12, further comprising a receiver member, the receiver member being located below the collected-toner outlet opening of the drum unit located inside the main-body housing, the receiver member being configured to receive the collected toner failing to enter the toner cartridge through the collected-toner inlet opening, wherein

20 in a state where the supporting member is located at the inner position, the supporting member is located between the collected-toner outlet opening and the receiver member in a vertical direction, and

25 in a state where the supporting member is located at the outer position, the supporting member is not located between the collected-toner outlet opening and the receiver member in the vertical direction.

30 14. The image forming apparatus according to claim 1, wherein

35 the photosensitive drum is rotatable on an axis extending in a first direction, and

the drum unit is a drum cartridge mountable in and demountable from the main-body housing in the first direction.
